ELECTRICAL TUBE-IMMERSION HEATER

Wytze Beje Smits, Amsterdam, Netherlands, and
James M. Beck, Birmingham, Ala.

Application August 15, 1946, Serial No. 691,086

8 Claims. (Cl. 219—41)

1

The object of our invention is to provide an electrical tube-immersion heater with very effective heat transmission and of great durability and to avoid the drawbacks and the difficulties in the manufacture and in the use of known constructions.

Said invention principally consists in the construction and arrangement of the heating elements. A further object of the invention is to provide pressure means for pressing the heating elements equally against the outer tube.

The invention further consists in certain details of construction and arrangement of parts as will be hereinafter more particularly described and claimed.

Referring to the accompanying drawing, which forms a part of the specification and on which similar reference characters indicate similar parts, Figure 1 is a vertical longitudinal section along the line I—I of Fig. 2. Fig. 2 is a top plan view. Fig. 3 is a vertical longitudinal section along the line III—III of Fig. 2. Fig. 4 is a cross-section along the line IV—IV of Fig. 3. Fig. 5 is a horizontal transverse section along the line V—V of Fig. 1. Fig. 6 is a side elevation of a preferred form of the heating element, showing this element in a flat condition, before inserting it into the tube. Fig. 7 is a vertical section along the line VII—VII of Fig. 6. Figures 8 and 9 show on an enlarged scale plan views of the pressure body before expanding and after having been expanded by a pressure pin. Figures 10 and 11 are like views of a modification. Fig. 12 is an elevation of the pressure pin.

Referring to the drawings, 1 is a cylindrical tube in the usual outside form of electrical tube-immersion-heaters. Inside of tube 1 there are a mica layer 2 and a bottom disk 2a of mica as outside insulation. Then follow concentrically from the outside towards the axis of the tube the heating element 3, a further insulation-layer 4 and a hollow cylindrical pressure body 5. This pressure body is expanded through a pressure pin 18, as will be described later on. Thereby the insulating material and the heating element are pressed equally against the tube 1 over the whole width of the element.

The heat element shown consists of four small individual elements *a*, *b*, *c*, *d*, which in a preferred form are connected in parallel. Each of these small elements has a narrow mica strip 6 wound with a thin heating wire 7, the ends of which lie in notches 8 of the strips. At the positions of the notches 8, a loop 9 of flat wire is laid all round the ends of the strips 6 and is spot

2

welded together at points 10 near the strips. To the free ends of the loops 9 the current supply wires 12 are spot welded. By this construction the single elements are held at exact distance from each other and an unwrenchable unit of the elements is obtained. Besides that the current supply wires cannot slide off the elements.

A special new construction was necessary for the pressure body 5. If one chooses springlike pressure means the elasticity would be eliminated due to the heating of the elements. Therefore a hollow split cylinder is chosen, which cylinder is expanded by a cylindrical pressure pin forced between the rims of the cylinder. The hollow cylinder shown especially in Figures 8 and 9 is formed from a thin iron sheet. The thickness of the sheet is important for the quality of the pressure and depends upon the diameter on which the pressure is applied. Is the sheet too thin it can easily crack at one point, if chosen too thick too much power must be applied to expand the cylinder.

From the split 13 of the cylinder 5 the ends of the sheet are directed as flanges 14, 15 towards the axis of the cylinder. The inner ends of these flanges are supported the one against the other. To this purpose the end of one flange, for example, flange 15, is bent to form a groove 16 which receives the end of the other flange. The flanges are further bent to form a groove 17 for inserting the cylindrical pressure pin 18. Figure 8 shows the pressure cylinder previous to fitting, and Figure 9 shows it expanded by the pressure pin. When pressing the pressure pin in the inner ends of the flanges cannot yield and therefore the pressure is exerted at the circumference of the cylinder, whereby the pressure body puts the heating element as well as the insulations under an equal concentric pressure.

Figures 10 and 11 show a modified pressure body construction with the same effect and the manufacturing speciality that these cylinders can be obtained by sawing off a thin-walled special drawn profile tube. Here, a continuous tube 5a is used having radially inwardly extending flanges 14a and 15a formed with matching grooves 17a.

The following advantages are obtained by the described construction of the heating element and the pressure means.

By dividing the heating element into a plurality, for example four individual elements, each of these elements is very small, so that the stress by the expansion and the contraction of the heating wire is decreased, as the distance between two crackpoints of the wire-winding is only

small. Therefore the durability of the heating element is very much increased.

The small elements are wound with a thin heating-wire, which has the advantage, that a thin wire can be more easily subjected to over-loading, due to current-variations, than a thick wire. There is also the low cost for the thin wire in comparison to other constructions which need a greater amount of metal.

A direct heating contact with the heating wire is obtained through the pressure body pressing the heating elements against the outside tubing, thus giving following advantages:

(a) The well cooled heating wire can more safely be subjected to an overloading and can from the beginning carry a higher current supply.

(b) The heating wire need not be brought to such a high temperature that the produced heat is mainly given off through radiation. This increases a great deal the durability.

(c) Advantage (b) means that the insulation is heated to a lower degree and can be applied thinner and cheaper.

(d) The thinner insulation affords a better heat transmission between heating wire and outside tubing which in turn gives the advantage of a cooler heating wire.

As there is nothing inside of the immersion-heater besides the thin hollow pressure body no heat can be otherwise conducted and all of the produced heat flows to the outside whereby a very high efficiency is reached.

Should one of the small parallel connected heating elements burn out, there are still for instance three more in operation. Through this construction the immersion-heater can be still used although its efficiency is decreased 25%.

A repair of the immersion-heater is possible without difficulties and at low costs. The pressure-pin is drawn out, a new heating element is inserted and the pin replaced.

The pressure pin (see Fig. 12) has at its one end a point 19 which fits into the groove 17 of the unexpanded pressure body 5 (see Fig. 8). That point passes over to the cylindrical pin by a small conical part, in order to expand the body 5 more easily. At its other end the pressure pin 18 has a threaded projection 20, with which the pin can be screwed into a long rod having inside-threading, so that after the complete heating element has been inserted into the tube 1, the pressure pin 18 can be easily inserted. In case of repairing the pin 18 can be removed by means of this rod and the heating element drawn out.

Into the upper end of the tube 1 an insulating piece 21 is inserted, and tightened and sealed by a small rubber ring 22. The piece 21 is flattened at one side as at 23 (see Fig. 4). A holding hook 24 for engaging the rim of a container is inserted into a positioning slot 25 of the upper rim of the tube 1. This hook has its inner lower end bent and this bend 26 engages a notch in the flattened side of the piece 21. In this way the insulating piece 21 is held in a determined position and at an always equal determined distance from the inserted heating-element. Over a trunnion 27 of the piece 21 a handle 28 is shoved. By three screws 29 the handle and the piece 21 are held in place in the tube and the holding-hook is held against outward movement by the handle. The current-supply-wires 12 are subjected shortly above the heating element to a sharp bend 30 over which a tubular spacer 31 of porcelain, glass or similar material of a chosen length is placed, which tubular piece in turn sets against the in-

sulating piece 21. The current-supply-wires 12 being conducted through the tubular piece 31, which has an insulating core, and through bores of the insulating piece 21 and are connected with the cable 32 in one of the usual ways within the hollow handle 28. Despite the simplicity of this fitting, the relief of tensile stress is so efficient that it is impossible to pull the current-supply-wires out and thereby to damage the heating element.

Pressure body 5, heating element 3 and insulating layers 2, 4 are inserted into the tube 1 at the same time and in such a manner that the joints of all these parts meet exactly at a place below the cut 25 in the tube. As the insulating piece 21 is held by means of the fastening hook 24 always in the same position no turning and consequently no touching of the current-supply wires is possible.

If the pressure cylinder 5 is expanded by inserting the pressure pin 18 the split or gap of the cylinder becomes broader. This gap has no disadvantageous effects as to the heat transmission of the heating element, as it is placed due to the above mentioned fitting at a point where no heating wire is present. At the places where heat is to be transmitted, an entirely equal pressure and therewith an equal heat transmission are assured by thus positioning the parts.

We prefer, as mentioned above, to connect the small individual elements in parallel, but in order to have an immersion-heater for various voltages the individual elements can be connected either in parallel or in series.

Having thus fully described our said invention, what we claim as new, and desire to secure by Letters Patent, is:

1. An electrical tube-immersion-heater, consisting of a cylindrical tube, a plurality of small heating elements within said tube, each of said elements having a narrow strip wound with thin heating wire and with small notches near its ends, in which notches the ends of the heating wire are held, a wire-loop embracing the ends of the strips and spot welded near the strips, means pressing the elements equally against the tube and means for adjusting the parts in the tube.

2. An electrical tube-immersion-heater, consisting of a cylindrical tube, a plurality of small heating elements within said tube, a hollow pressure cylinder within the elements, said cylinder being split longitudinally, a cylindrical pressure pin expanding the cylinder circumferentially and means for adjusting the parts within the tube.

3. An electrical tube-immersion-heater, consisting of a cylindrical tube, a plurality of small heating elements within that tube, a hollow pressure cylinder within the elements, said pressure cylinder having a longitudinal split and flanges extending inwardly towards the axis of the cylinder, the inner ends of these flanges are supported the one against the other a cylindrical pressure pin inserted between said flanges, and means for adjusting the parts in the tube.

4. An electrical tube-immersion-heater according to claim 3, the pressure body being a cut-piece of a special profile-tubing.

5. An electrical tube-immersion-heater according to claim 2, the pressure pin having a small point at one end and a screw projection at the other end.

6. In an electrical tube-immersion-heater the combination of a cylindrical tube, a plurality of narrow heating elements within the tube, means pressing the elements equally against the tube,

means for adjusting the parts in the tube, a slot in one end of the tube, and a holding hook fitting into said slot and serving as a guiding point in assembling the parts.

7. In an electrical tube-immersion-heater the combination of a tube, a plurality of narrow heating elements within the tube, means pressing the elements equally against the tube, an insulation piece extending into the upper end of the tube, a spacing piece between said insulating piece and the heating elements, and current-supply-wires passing through said pieces and connected to said heating elements.

8. In an electrical tube-immersion-heater the combination of a tube, a plurality of small heating elements within the tube, means pressing the elements equally against the tube, an insulation piece arranged at the upper end of the tube, current-supply-wires passing through separated bores of said piece, a holding hook attached to the tube which hook holds the insulation piece

in a settled position, and a handle fastened to the tube and overlapping the holding hook to hold it in position.
